US0D1091733S

(12) **United States Design Patent** (10) **Patent No.:** **US D1,091,733 S**
(45) **Date of Patent:** **** Sep. 2, 2025**

(54) **ANKLE ATTACHMENT FOR
WEIGHTLIFTING**

(71) Applicant: **Coulter Ventures, LLC.**, Columbus, OH (US)

(72) Inventors: **William Henniger**, Columbus, OH (US); **Laurie Ann Coughlan**, Westerville, OH (US); **Anelia Perez**, Hilliard, OH (US); **Tyler McClure**, Galena, OH (US); **Ahmik Jones**, Upper Arlington, OH (US); **Tim Martin**, Flanders, NJ (US)

(73) Assignee: **Coulter Ventures, LLC.**, Columbus, OH (US)

(**) Term: **15 Years**

(21) Appl. No.: **29/961,430**

(22) Filed: **Sep. 5, 2024**

Related U.S. Application Data

(63) Continuation of application No. 29/803,651, filed on Aug. 13, 2021, now abandoned.

(57) **CLAIM**

The ornamental design for an ankle attachment for weightlifting as shown and described.

DESCRIPTION

FIG. 1 is a top, front, right perspective view of an ankle attachment for weightlifting showing our new design;

FIG. 2 is a rear view thereof;

FIG. 3 is a front view thereof;

FIG. 4 is a right side view thereof;

FIG. 5 is a left side view thereof;

FIG. 6 is a top view thereof; and,

FIG. 7 is a bottom view thereof.

The broken lines within the claimed areas represent stitching that forms no part of the claimed design. The remaining broken lines in the drawings depict portions of the ankle attachment for weightlifting that form no part of the claimed design.

1 Claim, 7 Drawing Sheets
